(57) **CLAIM**

The ornamental design for a mushroom corer/brush, as shown and described.

DESCRIPTION

FIG. 1 is a top perspective view of the mushroom corer/brush showing our new design;

FIG. 2 is a right side view thereof;

FIG. 3 is a front view thereof;

FIG. 4 is a left side view thereof, the left side being identical to the right side view;

FIG. 5 is a rear view thereof;

FIG. 6 is a top view thereof; and,

FIG. 7 is a bottom view thereof.

The broken lines in the drawings depict structure that forms no part of the claimed design.
